(57) **CLAIM**

The ornamental design for an artificial bait, as shown and described.

DESCRIPTION

FIG. 1 is a front, bottom and left side perspective view of an artificial bait, showing my new design;

FIG. 2 is a rear, top and right side perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the artificial bait that form no part of the claimed design.
